ELECTROMAGNETIC LOCK

Jack Paterson James, Liverpool, England

Application August 9, 1938, Serial No. 223,988
In Great Britain September 13, 1937

10 Claims.

(Cl. 70—278)

The present invention relates to electromagnetic locks which are released by the energisation of a number of solenoids under the control of three or more manually operated switches or switch contacts and the invention is particularly suitable for use in connection with automobile vehicles for preventing theft thereof.

The invention may be used for the locking of any desired element of apparatus and in connection with automobile vehicles it may, for example, be used to lock the gear lever when the automobile is parked in a public space, in which case the locking member may consist of a slidable plate or bar which is forked so that in its released position it permits free manipulation of the gear lever while in its locked position it restricts the movement of the gear-lever.

It is an object of the invention to provide a lock with an electromagnetic releasing apparatus which will not only render the releasing of the lock a matter of difficulty to an unauthorised person but which will also provide for the operation of an alarm in the event of the lock being incorrectly manipulated.

It is an object of the invention to provide an electrically releasable lock embodying manually operated switches, a number of solenoids under the control of said switches, automatically operated switches each under the control of one solenoid and in the circuit of another to render the solenoids operable in predetermined sequence only to release the lock, a trip coil adapted when energised to render at least one of said solenoids inoperative to prevent release of the lock and so connected with at least two of said manually operated switches that closure of either of said two manually operated switches prior to closure of the automatic switch in the circuit of the solenoid controlled by such manually operated switch would cause energisation of the trip coil.

It is a further object of the invention to embody in such an electrically releasable lock at least one additional switch, similar in appearance to such manually operated switches and connected to the trip coil so as to energise the trip coil on closure of such additional switch.

More particularly, a lock is released by the energisation of at least three solenoids in predetermined sequence under the control of at least three manually operated switches, one in the circuit of each solenoid, energisation of a given one solenoid being adapted to cause closure of a break in the circuit of another solenoid, energisation of which, in turn, is adapted to cause closure of a break in the circuit of a third solenoid, while

at least the first solenoid is adapted to be rendered inoperative by the energisation of a trip coil which is connected for energisation thereof, with the manually operated switches of said second and third solenoids through contacts which are respectively opened on energisation of said first and second solenoids.

Preferably at least one of said solenoids, for example, the first, has a break in its circuit which is normally closed but is adapted to be opened by energisation of a trip coil. To render the release of the lock more difficult to an unauthorised person the trip coil may be connected, for energisation thereof, with an additional manually operated switch or switches indistinguishable from said first mentioned manually operated switches.

Operation of said additional switch or any of said additional switches or of any of said manually operated switches other than the first in other than the predetermined sequence may be adapted to cause energisation of the trip coil and closure of a switch controlling an audible or visible alarm device.

If desired three solenoids may be arranged in cascade. Preferably, the armatures of the first two solenoids energised in correct sequence are each adapted respectively to close a break in the circuit of the coil immediately succeeding and also to close a break in a hold-on circuit adapted for maintaining energisation of its own coil, the hold-on circuits of both of said coils including a switch or switches which can be opened by operation of said trip coil.

The said manually operated switches and said additional manually operated switch or switches may be embodied in a multiple switch capable of selective operation at predetermined positions for manual closure of breaks in the circuits of the respective coils or solenoids and capable of operation at other positions for energisation of the trip coil, whereby the lock can be released by selective operation of said multiple switch at predetermined positions in correct order, while operation of said switch at other positions than said predetermined positions or at said predetermined positions in incorrect order as described above with reference to said manually operated switches, is adapted to cause operation of said trip coil and of said alarm device.

The invention is more particularly described with reference to the accompanying drawings which illustrate examples of the invention suitable for use in connection with an automobile vehicle and in which:

Figure 1 is a wiring diagram showing one form of electric circuit according to the invention, in which the lock can only be released by operation of the manually operated switches in predetermined sequence.

Figure 2 is a wiring diagram of an alternative electric circuit.

Figure 3 illustrates the main switch governing the current supply.

10 Figure 4 illustrates a switch governing the current supply to the alarm circuit.

Figures 5 and 6 are a sectional elevation and plan view of a manual multiple switch control.

15 Figure 7 is a side sectional view of the locking unit.

Figure 8 is a corresponding end sectional view on the line 8—8 of Figure 7.

Figure 9 is a sectional plan view on the line 9—9 of Figure 7.

20 Figure 10 is a side sectional elevation being a modified arrangement for the control of the locking members as compared with that shown in Figure 7.

The mechanical part of the lock referred to generally as A shown in Figures 7, 8 or 9 has a main locking member 20 in the form of a flat plate, the main body 20a of which is freely slideable into guides 21, 22 formed in the sides 23, 24 of an inner casing, composed of the said side plates 23, 24 and two end plates 25, 26, and these plates are secured together by the housing 28 and base plate 29, the base plate being preferably welded to the housing 28, as indicated at 29a.

35 The locking unit A may be secured to the automobile vehicle by bolts 30 in such a position in relation to the gear lever 31 as to secure this lever in a given locked position usually the neutral position when the locking member 20 is in its projected or locked position when the V notch 20b of the locking member 20 is brought closely adjacent to or in contact with the said gear lever 31 as shown in Figure 9.

Referring to Figures 7 and 3 of the drawings, a 45 spring actuated cross bar 32 is slidably mounted in vertical guides 33, 34 in the side plates 23, 24 and is adapted to abut against one end 20c of the locking member 20 to secure the gear lever 31 in the neutral position.

50 The bar 32 is secured to one end of the armature 40 of a solenoid 41 so that when the authorised user desires to unlock the gear lever 31 this may be done by the correct operation of the electrical switch means (to be hereinafter described) 55 to cause the magnetic coil 41 to be energised and thereby to withdraw the armature 40 and the locking bar 32 connected therewith against the action of the spring 142, from contact with the locking member 20 to allow this to travel down its guide 21, 22 by means of a spring 11 to release the gear lever 31. Thus the locking member 20 is withdrawn from its projected position by means of the spring and may, if desired, be substantially horizontally disposed instead of inclined as shown in Figure 7. Alternatively the locking bar 20 may be adapted to be withdrawn by the armature of an electromagnetic coil, energised simultaneously with the solenoid 41.

70 In the alternative form of construction shown in Figure 10 the locking member 20 is locked in its projected position by means of a spring actuated lever 37 which is pivoted at 38 to the side plates of the inner casing and which has an up-standing projection 39 adapted to abut against 75 the end 20c of the locking member 20 whereby

to prevent movement of the gear lever from the neutral position.

The free end of the lever 37 is connected to one end of the armature 40 of a solenoid 41. The lever 37 is normally urged in an upward 5 direction by means of a spring 142.

The electromagnetic coil or solenoid 41 and its armature 40 are diagrammatically shown in Figure 1 which illustrates one form of electromagnetic lock releasing circuit according to the invention. The energisation of the coil 41 is dependent upon the previous energisation of coils 42, 43 in correct order i. e. coil 42 first and coil 43 second. The coils 42, 43 and 41 are respectively in circuit with manually operable switches 15 or switch contacts 52, 53 and 51. If the switches 52, 53 and 51 are closed in the sequence 52, 53, 51 then the coils 42, 43 and 41 will be energised in correct sequence to release the lock. If the switches 53, 51 are operated in incorrect sequence then a coil 44 will be energised to operate an alarm and a trip coil 45 will be energised as will be described later.

In order to make it difficult for an unauthorised user to select the correct switches for operation, 25 more manually operated switches are provided than are required for releasing the lock.

In Figure 1 a switch 54 is shown as indicating either one or a number of additional switches arranged in parallel all of which are unnecessary 30 for the correct operation of the lock.

The apparatus of the invention is operated by an electric accumulator 60 which may be the ordinary accumulator of an automobile vehicle and it is also operable by an auxiliary accumulator 61 which may be concealed. The provision of a concealed auxiliary accumulator is not of course essential but is advisable since it would enable the warning device to be operated even though the ordinary accumulator were disconnected by an unauthorised person attempting to tamper with the lock.

Current is fed to the electrical apparatus of the invention through a switch 63 which is normally open, and closed only when the locking 45 member 20 is in its projected position. This switch is shown in more detail in Figure 3 wherein the locking member 20 is in its withdrawn or unlocked position. When the locking member is moved towards the left into its projected position the switch lever 64 is angularly displaced in an anticlockwise direction under the influence of a spring 65, operating through an arm 66 rigidly connected to the lever 64, whereby the terminals 67 are brought into contact with the terminals 55 68 which feed the circuit. A similar switch 69 controls the supply of current to an alarm device 70 shown in Figure 1. The switch 69 is shown in more detail in Figure 4 and normally remains open when the locking member 20 is withdrawn 60 to unlocked position. When the locking member 20 is projected the switch 69 is available for closure but is not actually closed until the coil 44 is energised to cause a downward movement of the armature 70a as viewed in Figure 4 and 65 angular displacement of the switch lever in an anticlockwise direction. The switch levers of the switches 63 and 69 are provided respectively with insulating sheaths 63a, 69a where they contact 70 with the locking member 20.

Assuming that the locking member 20 is in its projected position, thereby allowing switch as shown in Figure 3 to close the correct operation of the switch gear shown in Figure 1 is as follows:

The switch 52 is first of all closed and the circuit of the coil 42 is completed from the return 71 through the conductor 72, switch 52, conductor 52a, contact 73a, armature head 73, contact 73b and conductor 74. The energisation of the coil 42 moves armature head 76 down to close contact pair 77 and contact pair 78 whereupon the manual switch 52 can be released and the return circuit of the coil 42 is maintained through conductor 74, contact 73b, armature head 73, contact 73a, conductor 79, contact pair 78 and conductors 80 and 72 to the return 71. The closure of contact pair 77 prepares the circuit of coil 43 for energisation by closure of the switch 53, whereupon the circuit of coil 43 is completed from the return 71 through a conductor 72, switch 53, conductor 53a, contact pairs 77 and the conductors 81 and 82. The armature head 83 of coil 43 then moves down to close contact pairs 84 and 85, whereupon the switch 53 can be released and the return circuit of coil 43 is maintained through conductors 82 and 82a, contact pair 85, conductor 86, contact pair 78 and conductors 80 and 72 to return 71.

The closure of contact pair 84 prepares the circuit of coil 41 for energisation by closure of switch 51 whereby the circuit of coil 41 is completed from 71 through conductor 72, switch 51, conductor 87, contact pair 84 and conductor 88.

It will be appreciated that there is a potential current supply to all the coils shown in Figure 1 when the switch 63 is closed, this current supply taking place through conductors shown in dotted lines.

It will be appreciated that in order to release the lock, the switches 52, 53, 51 must be operated in the order 52, 53, 51 and if for example, the switch 51 had been closed immediately after energisation of the coil 42, the coil 42 would have been de-energised by energisation of the trip coil 45, through conductors 90, 91 and 92, contacts 93 and the top contact 84, conductor 87, switch 51, conductor 72 and return 71, causing movement of the armature head 73 downwards to disconnect the contacts 73a and 73b which are normally bridged by the armature head 73 thereby breaking the hold-on return circuit of the coil 42. Moreover such closure of switch 51 would also have formed a return for the coil 44 through conductor 87 the contact pairs 93, conductors 92, 91 and 91a, thereby closing the switch 69 and putting the alarm device 70 into operation which may of course be either optical or audible or both.

If the switch 51 were closed prior to closure of the switch 52, the alarm device would be put into operation, and the trip coil 45 energised but of course the energisation of the trip coil would be of no effect if no other coil had been previously energised.

Again, if the switch 53 were closed prior to closure of switch 52 and energisation of coil 42, the coil 45 would be energised through conductors 90, 91, contact pair 71a, the upper contact 71, conductor 53a, switch 53, conductor 72 and return 71. Coil 44 would also be energised since the returns of coils 44 and 45 are permanently interconnected by conductors 91a, 91 and 90.

If any of the switches 54 (only one of which is illustrated in Figure 1) were to be operated prior to release of the lock and prior to opening of the switch 63 the coil 44 would be energised through conductors 91a, 91, switch 54, conductor 72 to return 71 and moreover if the coil 42

or the coils 42 and 43 had been previously energised they would be de-energised by energisation of the trip coil 45 and movement of the armature 73 downwards, since the return of coils 44 and 45 are permanently interconnected through conductors 91a, 91, and 90. Thus, with the switch 63 closed operation of the switch 53 prior to operation of the switch 52 or operation of the switch 51 prior to operation of switches 52, 53 in the order 52, 53, or operation of the switch or switches 54 at any time, would cause energisation of the coil 44 and operation of the warning device 70 and moreover any such incorrect operation would cause energisation of the coil 45 and de-energisation of the coil 42 or of the coils 42 and 43 if previously energised by successful operation of the switch 52 or of the switches 52 and 53.

The upper contact 77 is electrically connected with the lower contact 77a and both are insulatedly mounted on the armature head 76. Similarly the upper contact 84 is connected with the lower contact 93 and both are insulatedly mounted on the armature head 83. The contacts 73a, 73b are not mounted upon the armature head 73 but contact with and are bridged by the head 73 when the head is in its normal projected position shown in Figure 1.

Figure 2 illustrates a different arrangement of the coils 41, 42, 43, 44 and 45 which enables the results achieved by the arrangement of Figure 1 to be obtained but necessitates the provision of three additional coils 98, 99 and 100. The elements of Figure 2 which correspond to elements of Figure 1 are similarly referenced. The correct operation of the apparatus of Figure 2 is as follows:

The switch 52 is first of all closed to energise the coil 42 and the return from coil 42 takes place first of all through conductors 100, 101, 102, contacts 101 and armature head 102 and switch 52 to return 71, whereupon the armature head 102 bridges the contacts 102 so that the switch 52 can be released the return being established through conductors 100, 103, contacts 102, 104, bridged by armature head 102, conductor 104, contacts 95 bridged by trip coil armature head 103 and through conductor 105, to return 71.

The energisation of coil 42 and the bridging of contacts 102 closes one break in the circuits of coils 43 and 99 and prepares them for energisation by energisation of coil 98.

Switch 53 is then depressed to energise coil 98. The energisation of coils 43 and 99 is dependent upon prior energisation of coil 42 and of coil 98, the armature head 106 of which bridges contacts 107 to provide return for coils 99 and 43 through conductors 107a, 107b, 108, contacts 107 bridged by armature head 106, conductors 109, 110, 103, contacts 102 bridged by armature head 106, conductor 104, contacts 95 bridged by armature head 106 and conductor 105 to return 71. As soon as armature head 106 of coil 43 is closed the switch 53 can be released, the return for coils 99 and 43 being then established through conductors 107a, 107b, 112, armature head 106, conductors 113, 110, 103, armature head 106, conductor 104, armature head 106 and conductor 105, to return 71. As soon as switch 53 is released the armature head 106 of coil 98 will move out of contact with contacts 107, the hold-on circuits of coils 43 and 99 being now completed independently of armature head 106.

The coil 41 is now prepared for energisation

and can be energised by depression of switch 51 which establishes a return circuit for coil 41 through conductor 114, contacts 111a, bridged by armature head 111, conductor 115 and switch 51 to return 71.

Similarly as in Figure 1, if any of the switches 54 is depressed or if either of the switches 53, 51 is depressed in incorrect sequence, the coil 44 will be immediately energised to close the alarm supply switch 69 and moreover the trip coil 45 will be energised to break any return hold-on circuit which may have been previously established and maintained through bridging of the contacts 95 by armature head 73. Thus if the coil 42 or the coils 42, 43 and 99 had been previously energized they would immediately be de-energised.

As will be observed the return ends of coils 44 and 45 are connected by conductors 120, 121 and 122 which conductors are connectable to the return 71 either directly through switch 54 or through switch 51 if coils 43 and 99 have not been energised, or through switch 53 if coil 42 has not been energised.

25 In connection with both Figure 1 and Figure 2 the returns 71 in the case of a two pole wiring system would be constituted by or connected to a common bus bar which would be connected through the manual control of the present invention, with that pole of the accumulator, whether positive or negative, opposite to that connected to the switch 63. In the case of single pole wiring systems the returns 71 would be constituted by or connected through the control to 30 the metallic casing or framework of the apparatus of the vehicle in which it is installed, such casing or framework being connected to that pole of the accumulator opposite to that connected to the switch 63.

40 In both Figures 1 and 2 the switches 51, 52, 53, 54 are understood to be spring-loaded so as normally to remain open. The armatures of coils 42, 43, 45, 98, 99 and 190 are spring-loaded so as to remain in a projected position.

45 The locking bar 32 connected to armature 40 of coil 41 is spring loaded so as normally to maintain armature 40 in its projected position. The armature 70a of coil 44 is counterbalanced by the lever of switch 69 so as normally to keep the armature 70a in its projected position. When energisation takes place the movable blades of switch 69 engage the fixed spring blades thereof, the interengagement of such blades preventing return of the armature 55 70a to its projected position until the locking member 20 is withdrawn.

50 It will be appreciated that for the successful operation of the apparatus of the present invention to release the lock three switches 51, 52, 53 only are necessary but in order to make it more difficult for an unauthorized person to release the lock a large number of similar switches are preferably provided, for example, there may be twenty or more switches 54 which 60 are identical in appearance to the switches 51, 52 and 53. A number of such switches are illustrated in Figures 7, 8 and 10 as being disposed at the top of the casing 28, each switch consisting of a fixed contact 130 and a movable contact 131 forming the end of a depressible plunger 132.

55 Preferably however such switches are embodied in a single control unit illustrated in Figures 5 and 6 wherein the fixed contacts of all the switches 54 are replaced by a conducting ring

135 whilst the fixed contacts of the switches 51, 52, 53 are replaced by contact elements 151, 152 and 153 which are mounted in but insulated from the conducting ring 135. The movable contacts of all the switches 51, 52, 53, 54 are embodied in a rotatable contact arm 136. The ring 135, contacts 151, 152, 153 and the rotatable contact arm 136 are concealed within a casing 137 which contains an insulating ring or block 138 in which the contact ring 135 is mounted. 10 The contact arm 136 is connected to a central spindle 139 which is operable from the exterior of the casing 137 by a knob 140 which is provided with a pointer 141. The engagement of the contact arm 136 with the contact ring or 15 with any of the contacts is rendered effective by axial movement of the spindle 139 against the action of spring 142 to bring the end 143 of the spindle 139 into contact with the metallic closure disc 144 of the casing 137. Thus selection of contacts is effected by rotation of the spindle 139 while the actual closure of a circuit through such contact is effected by axial displacement of the spindle 139.

20 The casing 137 is provided on its exterior with a scale 150 to enable an authorised user to locate the contacts 151, 152, 153. The effect of providing a large number of graduations or numerals on the scale 150 is similar to the effect of providing a large number of contact switch 30 plungers 132 as shown in Figures 7, 8 and 10.

25 In connection with the arrangement shown in Figure 1, it is obvious that if desired, the coil 44 operating the alarm switch 69 may be eliminated and the alarm switch 69 operated by the 35 armature of the trip coil 45.

I declare that what I claim is:

1. In an electrically releasable lock, at least three solenoids, at least three manually operated switches arranged one in the circuit of each solenoid, and electrical connections for the said solenoids whereby energisation of a given one of said solenoids is adapted automatically to close a break in the circuit of a second solenoid which in turn is adapted to close a break in the 45 circuit of a third solenoid whereby the lock can be released by energisation of said solenoids in predetermined sequence, a trip coil which is adapted, when energised, to render said first mentioned solenoid inoperative and which is normally connected, for energisation thereof, with the manually operated switches of said second and third solenoids and contacts automatically operated between said trip coil and the manually operated switches of said second and third 50 solenoids, said contacts being opened on energisation of said first and second solenoids respectively in order to disconnect the trip coil from said respective manually operated switches.

2. In an electrically releasable lock, at least three manually operated switches, a number of solenoids under the control of said switches, a trip coil which is normally connected, for energisation thereof, with at least two of said manually operated switches and adapted, on energisation thereof, to render at least one of said solenoids inoperative and electrical connections including automatically operated contacts between said switches, coil and solenoids whereby the lock can be released by correct operation of 70 said manually operated switches in predetermined sequence only and provided there is no intermediate operation in its wrong order of a manually operated switch, not previously operated in the sequence, said solenoid which is 75

adapted to be rendered inoperative by said trip coil having a break in its circuit which is normally closed but opened on energisation of the trip coil.

3. In an electrically releasable lock, at least three solenoids, at least three manually operated switches arranged one in the circuit of each solenoid, and electrical connections for the said solenoids whereby energisation of a given one of said solenoids is adapted to close a break in the circuit of a second solenoid which in turn, is adapted on energisation automatically to close a break in the circuit of a third solenoid whereby the lock can be released by energisation of said solenoids in predetermined sequence, a trip coil which is normally connected, for energisation thereof, with the manually operated switches of said second and third solenoids, automatically operated contacts between said trip coil and the manually operated switches of said second and third solenoids, said contacts being opened on energisation of said first and second solenoids respectively in order to disconnect the trip coil from said respective manually operated switches and contacts in the circuit of the first mentioned solenoid, which contacts are normally closed but opened on energisation of the trip coil to render said solenoid inoperative.

4. In an electrically releasable lock, at least three solenoids, at least three manually operated switches arranged one in the circuit of each solenoid, normally open hold-on circuits for at least two of said solenoids, and electrical connections for the said solenoids whereby energisation of a given one of said solenoids is adapted to close its own hold-on circuit and to automatically close a break in the circuit of a second solenoid which in turn is adapted on energisation to close its own hold-on circuit and automatically to close a break in the circuit of a third solenoid whereby the lock can be released by energisation of said solenoids in predetermined sequence, a trip coil which is adapted, when energised, to render said first mentioned solenoid inoperative and which is normally connected, for energisation thereof, with the manually operated switches of said second and third solenoids and contacts between said trip coil and the manually operated switches of said second and third solenoids, said contacts being opened on energisation of said first and second solenoids respectively in order to disconnect the trip coil from said respective manually operated switches.

5. In an electrically releasable lock, at least three solenoids, at least three manually operated switches arranged one in the circuit of each solenoid, normally open hold-on circuits for at least two of said solenoids, at least one additional switch similar in appearance to said manually operated switches, and electrical connections for the said solenoids whereby energisation of a given one of said solenoids is adapted to close its own hold-on circuit and to close a break in the circuit of a second solenoid which in turn is adapted to close its own hold-on circuit and to close a break in the circuit of a third solenoid whereby the lock can be released by energisation of said solenoids in predetermined sequence, a trip coil which is adapted, when energised, to render said first mentioned solenoid inoperative and which is normally connected, for energisation thereof, with said additional switch and with the manually operated switches of said second and third solenoids, contacts between said trip coil and the manually operated switches of said second and third solenoids,

said contacts being opened on energisation of said first and second solenoids respectively in order to disconnect the trip coil from said respective manually operated switches, a warning device and a switch controlling said warning device and adapted to be automatically closed on energisation of the trip coil whereby to operate the warning device.

6. In an electrically releasable lock, manually operated switches, a number of solenoids under the control of said switches, automatically operated switches each under the control of one solenoid and in the circuit of another to render the solenoids operable in predetermined sequence only to release the lock, a trip coil adapted, when energised, to render at least one of said solenoids inoperative to prevent release of the lock and so connected with at least two of said manually operated switches that closure of either of said two manually operated switches prior to closure of the automatic switch in the circuit of the solenoid controlled by such manually operated switch would cause energisation of the trip coil.

7. In an electrically releasable lock, manually operated switches, a number of solenoids under the control of said switches, automatically operated switches each under the control of one solenoid and in the circuit of another to render the solenoids operable in predetermined sequence only to release the lock, a trip coil adapted, when energised, to render at least one of said solenoids inoperative to prevent release of the lock and so connected with at least two of said manually operated switches that closure of either of said two manually operated switches prior to closure of the automatic switch in the circuit of the solenoid controlled by such manually operated switch would cause energisation of the trip coil and at least one additional switch, similar in appearance to said manually operated switches, connected to said trip coil to energise the trip coil on closure thereof.

8. In an electrically releasable lock, a multiple switch embodying a number of manually operated switch elements, a number of solenoids under the control of said switch elements, automatically operated switches each under the control of one solenoid and in the circuit of another to render the solenoids operable in predetermined sequence only to release the lock, a trip coil adapted, when energised, to render at least one of said solenoids inoperative to prevent release of the lock and so connected with at least two of said manually operated switch elements that closure of either of said switch elements prior to closure of the automatic switch in the circuit of the solenoid controlled by such manually operated switch element would cause energisation of the trip coil.

9. In an electrically releasable lock, a multiple switch embodying manually operable lock releasing switch elements and at least one manually operable additional switch element, a number of solenoids under the control of said lock releasing switch elements, automatically operated switches each under the control of one solenoid and in the circuit of another to render the solenoids operable in predetermined sequence only to release the lock, a trip coil adapted, when energised, to render at least one of said solenoids inoperative to prevent release of the lock and so connected with at least two of said lock-releasing switch elements that closure of either of said two lock-releasing switch elements prior to closure of the automatic switch in the circuit of the solenoid controlled by such lock releasing switch element would cause

energisation of the trip coil, said trip coil being also connected to said additional switch element so that closure of said additional switch element is adapted to energise the trip coil.

5. 10. In a lock according to claim 7, a multiple switch embodying said manually operated switches and said additional switch comprising a contactor ring forming part of the additional switch, a number of contacts insulatedly mount-

ed in said contactor ring and serving as parts of the respective manually operated switches, a casing concealing said contactor ring and contacts, a rotary control operable from the exterior of the casing and a contactor arm connected to said control and adapted selectively to form the complementary part of said respective switches.

JACK PATERSON JAMES.
